[57] CLAIM

The ornamental design for a covered food tray, as shown and described.

DESCRIPTION

FIG. 1 is a top plan view of a covered food tray showing my new design;

FIG. 2 is a side elevational view thereof;

FIG. 3 is a right end elevational view thereof, the left end elevational view being a mirror image thereof;

FIG. 4 is a bottom plan view thereof; and

FIG. 5 is a sectional view taken along line 5—5 of FIG. 1.
